[57] CLAIM

The ornamental design for the fishing rod handle protector, as shown and described.

DESCRIPTION

FIG. 1 is a front elevational view of the fishing rod handle protector showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The cross-hatching on the top surface of the fishing rod handle protector in FIGS. 1, 2 and 5 represents a textured surface.
